FEEDING MECHANISM

Moses D. Heyman, Hewlett, N. Y., assignor of
one-half to Irene K. Heyman, Hewlett, N. Y.

Application June 20, 1936, Serial No. 86,275

13 Claims. (Cl. 164—87)

This invention relates to mechanisms for feeding relatively small irregular shaped pieces of stock to a punch press. While the mechanism as herein disclosed contemplates the feeding of mica, it is apparent that the invention may be employed with other types of material where difficulty is encountered in safely feeding such pieces to a press.

The long felt need of a device as herein contemplated will become readily apparent when it is understood that mica which is mined in pieces of varying sizes, only has a commercial market in the larger sizes, since it is only these sizes that may be safely handled in punch presses. However, the smaller pieces of mica, though large enough to form certain commercial parts, cannot at present be safely handled since the punch press operator can only position said small pieces on the die of the press by hand. This manual feed has proven quite dangerous, causing a considerable loss to the manufacturer in working time, insurance compensation, etc., and to the operator in mutilated hands, as can be well understood.

The present invention therefore seeks to provide a mechanism, either in form of an attachment to a punch press or as an integrally designed portion thereof, through the medium of which an operator may safely and rapidly feed small, irregularly shaped pieces of mica to be operated on by the press.

The invention also contemplates the provision of means, controlled by the feeding mechanism, for tripping the press in synchronous relation with the movements of the feeding mechanism parts.

Another contemplated feature resides in the employment of vacuum means for effecting the transfer of the mica pieces to the press.

More specifically the invention contemplates a device wherein the operator may place a piece of mica or the like upon a replica or close simulation of the part produced by the press at a point considerably remote from the punch and die thereof, means for transferring said piece of mica to be acted upon by the punch and die, and means for removing the finished mica part from the die and for disposing of the resultant scrap or fragment of mica to leave said die clear for the reception of an oncoming mica piece.

The accompanying drawings, which, though considerably detailed and illustrating a feeding mechanism as at present contemplated, are intended only as an example of a preferred manner of accomplishing the purposes of invention,

The arrangement and proportion of the parts may be varied to suit the application of the invention, and these drawings together with the following detailed specification should be treated as exemplary only.

In the drawings:

Figure 1 is a front elevational view of a feeding mechanism constructed in accordance with this invention.

Figure 2 is a top plan view thereof, partly in section, showing its application to a punch press.

Figure 3 is a plan sectional view as taken substantially along the line 3—3 of Figure 1.

Figure 4 is a side elevational view as seen from the left of Figure 1.

Figure 5 is a vertical sectional view as taken along the line 5—5 of Figure 2.

Figure 6 is a vertical sectional view as taken substantially along the line 6—6 of Figure 2.

Figure 7 is an elevational view of one of the 20 pneumatic or vacuum controlled valves shown in Figure 6.

Figure 8 is a fragmentary vertical sectional view showing the means for removing scrap material from the vicinity of the die.

Figures 9 and 10 are respectively enlarged detailed sectional views of the transfer and removal arm suction heads.

Figure 11 is a semi-diagrammatic view of a punch press equipped with a feeding mechanism 30 as contemplated in this invention.

In greater detail, the punch press platen A which supports the die B is usually formed with a front face C. In the present instance this face is utilized for the securing of a bed or frame 15 in fixed relation to the punch press and hence to the die, the bed being provided with a vertical flange 16 cooperating with the platen face C for this purpose.

Secured to the frame 15 are means such as a 40 plurality of tube or rod separators 17 to which are secured a sub-base 18. In order to insure rigidity to the above described assembly of base and sub-base, adjustable supports in the form of jacks such as shown at 19 may be interposed between the bottom of the sub-base and the floor upon which the press is supported. These jacks may also serve to afford accurate vertical positioning of the mentioned base assembly which, when thus positioned is fixedly bolted to the press 50 platen.

Upon the base 15 and supported in journals 20, there is carried a cam shaft 21 upon which is mounted the loose drive pulley 22 having a clutch member 23. Upon an extension 24 of the cam 55

shaft there is slidably keyed as at 25 a clutch member 26, having engagement with the clutch member 23, and provided with a spool 27. In the groove of the spool are arranged pins 28 carried on a fork 29, preferably pivoted as at 30 to a bracket mounted upon the floor. A spring 31 serves to maintain the clutch members in disengaged relation and they are maintained in engaged relation by the depressing of a foot pedal 32 which, through a connection such as the cable 33, is designed to force the clutch fork 29 to urge the clutch member 26 against the spring 31 to engage the clutch member 23.

The pulley 22 may be driven from an overhead shaft and the flywheel D of the punch press is similarly driven. However it may be arranged to provide a belt 34 between the pulley 22 and flywheel D so that the feeding mechanism is driven from the press.

Above the bed or frame 15 there is mounted a rotatable table 35, this table being mounted upon a spacer 36 to which is also affixed a ratchet wheel 37. The table and spacer are preferably affixed to each other as by means of bolts 38 and together are arranged to rotate about a fixed hollow sleeve 39 carried by the bed. The table is arranged to be intermittently rotated by means of a cam 40 on the cam shaft 21. Upon each revolution of said cam shaft, a roller 42 on a slide 43 is engaged by said cam. The slide also carries a spring tensioned dog 44 having engagement with the teeth of the ratchet wheel 37. Spring means such as shown at 45 serves to retain the roller 42 against the contour of the cam 40.

The table 35 is provided, adjacent its peripheral edge, with a plurality of stock receiving stations 46, and it is desired in the present instance to form these stations as replicas or close simulations of the ultimate part produced in the die of the punch press. These may either be painted on the table or applied to the surface thereof in any suitable manner.

As illustrated, the number of stations is commensurate with the number of teeth on the ratchet wheel and hence each reciprocation of the slide 44 will cause an advancement of the table a distance equivalent to a spacing between two stations.

A transfer arm 47 is mounted for oscillation upon the bed 15 and is oscillated about its center by the following mechanism driven by a crank 48 on the cam shaft 21.

The crank 48 is connected by means of a link 49 to a reciprocating slide 50, said slide being provided with a cam 51 which engages a cam roll upon an arm 52 fixed on a sleeve 53 forming the vertical portion of the transfer arm 47. To insure contact of the cam follower against the cam 51 at all times, another arm 54 on the sleeve 53 is connected to a pilot rod 55 upon which is positioned a coil spring 56 located between an abutment 57 upon said pilot rod and a fixed abutment 58. Hence, the cam 51 serves to move the arm 47 against the spring in one direction and the spring 57 serves to move the arm as controlled by the cam in the other direction.

The removal arm 59 which is carried on a sleeve 60 within the sleeve 39 is also mounted for oscillation as by the following mechanism. The slide 50 is provided with another cam 61 which is engaged by a cam follower on the end of an arm 62 fixed on a vertically mounted sleeve 63. This sleeve is also formed with an arm 64 substantially parallel to the arm 62 and a link connection 65 is made between the end of the arm 64 and an inter-

mediate point 66 of the removal arm 59. A third arm 67 is also provided on the sleeve 63, and to this arm there is pivoted a pilot rod 68 upon which is strung a coil spring 69 positioned between a shoulder 70 on the pilot rod and a fixed abutment 71.

From the foregoing it can be seen that the cam 61 serves to move the removal arm 59 against the spring in one direction, and the spring serves to urge the removal arm 59 as controlled by the cam 60 in the other direction.

The arm 47 is also arranged, in addition to its oscillatory movement, for vertical movement. This is accomplished through the medium of a cam 72 carried by the slide 50 engaging a roller on one arm 73 of a bell crank lever pivoted at 74, the other arm of said lever being forked as at 75 and provided with inwardly inreaching pins 76 for engagement with a spool 77, said spool being mounted for vertical movement upon a vertical sleeve 78. Upon this sleeve is also mounted the transfer arm sleeve 53. The upper end of the fixed sleeve 78 is provided with an abutment 79, and between said abutment and the sleeve 53 there is arranged a coil spring 80. Hence, it will be seen that the arm 47 is not only arranged for oscillation around the fixed sleeve 78 but may be moved vertically in both directions as controlled by the cam 72 and the spring 80.

The removal arm 59 is also mounted for vertical reciprocation. The cam 61 on the cam shaft 21 is arranged to engage a roll 82 on a push rod 83 mounted for vertical but non-rotational movement in the bed 15. This push rod is provided with a lower end 84 adapted for engagement by an adjustable screw 85 on one end 86 of a bell crank lever pivoted at 87 and forked as at 88, said forked end being provided with inreaching pins 89 engageable in a spool 90 carried on the end of the vertically movable sleeve 60. Between said spool 90 and abutment 91 there is arranged a coil spring 92. It is apparent from the above that the cam 61 serves to raise the sleeve 60, and hence the removal arm 59 against the spring 92, said spring serves to lower said arm under the control of said cam.

It should be understood that the movements of the two arms 47 and 59 are arranged in a certain preferred synchronous relation which is substantially as follows.

Starting with the arm 47 in the position shown in Figure 2, said arm first moves down to contact a piece of stock at that station to lift said stock in a manner later to be described; it is then moved upwardly with said stock and is rocked so said stock is centered upon the die B. When in this position it is again moved downwardly to deposit the stock upon the die and then moved upwardly and swung back to its initial position.

During the latter part of the motion of the arm 47, the arm 59 which has removed a finished piece of work from the die, starts from its position shown in Figure 2 to swing towards the die and then down to pick up a finished piece of work. It then moves up and across to the right where the work which it carries is dropped. During the period when both of said arms are remote from the die, that is when the arm 47 is moving towards the table and the arm 59 is starting towards the die, the punch press is arranged to operate upon the piece deposited by the arm 47 and the punch of said die is arranged to return to its elevated condition before the removal arm 59 arrives to remove the finished work. It will be noted therefore that it is desired to have the cam 75

shaft which controls the movements of the arms 47 and 59, also controls the punch press which is of the one revolution type. For this purpose a cam 93 is provided on the cam shaft 21, said cam having a lug arranged, upon each revolution of the cam shaft, to depress a lever 94 pivoted at 95 to the punch press and connected to the press clutch release rod 96. Upon said release, in the usual manner the press will perform its single cycle of operation, that is, a depression and elevation of the punch member.

The foregoing is descriptive of the mechanical features of the mechanism, and it is apparent therefrom that considerable changes in design may be effected without departing from the principles of the invention as contemplated.

In the present instance it is preferred to employ vacuum means for the purpose of effecting the transfer of the stock to the die and the finished work from the die to a point of disposal.

While outside means for providing vacuum or suction might be employed, it is preferred, in the present instance, to provide a vacuum pump 97 driven by an electric motor 98, both said pump and said motor being preferably supported upon and carried by the sub-base 18. The suction provided by the pump 97 is preferably applied through a filter chamber 99 connected to said pump as at 100. A connection 101 is made from said filter chamber to the upper part of a vacuum control valve body 102 and a similar connection 103 is made to another vacuum control valve body 104.

Both of these valve bodies are substantially similar in construction and therefore a description of one would suit the other. The suction on the line 101 is therefore applied in the chamber 105 of the valve body 102, and hence upon the upper face 106 of a piston valve 107 held by said suction and by a coil spring 108 against seat 109. Further serving to retain said valve in its elevated position against the seat 109, it is preferred to freely admit atmospheric pressure to the inner hollow portion of said valve as through the passage 110.

The valve 107 is provided with a series of circumferentially arranged ports 111 which, when the valve is in elevated position, communicate the mentioned atmospheric pressure through the passages 112 to a piping connection 113 which is connected to the hollow of the vertical sleeve 60 upon which is carried the removal arm 59. A connection 114 is made between said sleeve 60 and the chamber 115 in the suction head 116 of said removal arm.

To said head may be applied a fitting 117 designed to suit the shape and size of the work-piece to be handled.

It is apparent from the above that with the valve 107 in the elevated position, atmospheric pressure will enter through the port or passage 110 to fill the passages 112, connection 113, sleeve 60, connection 114, and fitting 117. In order to apply suction through the mentioned passages and connections, the valve 107 is depressed through the medium of a cam 118 on the cam shaft 21, said cam acting upon a roller 119 on a pivoted arm 120 bracketed as at 121 to the vacuum control valve body 102. The arm 20 engages a valve stem 122 which, passing through a stuffing box 123, engages the top of the valve 101 to depress it as shown in the dotted lines of Figure 7. The ports 111 will be cut off from the passages 112 to seal said passages against atmospheric pressure and the suction which has

been applied through the connection 101 to the chamber 105 will now be applied to said passages and to all the connections previously mentioned so that a work-piece which is in contact with the fitting 117 will be held thereagainst by the lack of pressure in the mentioned passages and connections, and by the atmospheric pressure which is normally exerted on the outer face of said work piece.

Thus it can be seen that under the control of the cam 118, suction is applied to the fitting 117 when the removal arm is moved down over the die to pick up a finished work piece therefrom, and the design of the cam 118 is such that the suction will be maintained until said arm 15 has swung to the position shown in the broken lines of Figure 2 where the suction is broken to permit the piece to fall away from said fitting. If it is found, however, that said piece might be inclined to stick, simple means may be utilized 20 for either jogging said arm or for brushing the piece therefrom.

In the manner above described, suction may also be applied to the head 124 of the transfer arm 47 but in this instance the suction is applied through the connection 103 and is controlled by the valve mechanism 104 through the medium of the cam 125 on the cam shaft 21.

To insure that the die is free of all the scrap or waste pieces resulting from the punching 30 operation after the removal of the punching, it is desired to provide means for removing said pieces and a preferred manner of accomplishing this is shown in Figures 2 and 8. The cam shaft 21 is provided with a cam 126 which rocks a lever 35 127 pivoted at 128 to a valve body 129 fastened to the wall 16 of the bed 15. The lever 127 is provided with an adjustable screw 120 engageable against a valve stem 131 carrying a valve 132 cooperating with a valve seat 133 in the body 129. 40 A chamber 134 on one side of the valve 130 is connected to a source of air pressure supplying air to said chamber through conduit 135. At the other side of the valve 131 there is arranged another chamber 136 to which is connected a fitting 45 137 having an elongated nozzle portion 138 which is directed towards and across the top face of the die. A coil spring 139 is arranged in the chamber 134 for maintaining the valve 131 upon its seat.

In operation and in synchronization with the movement of the removal arm, the cam 126 acts to unseat the valve 131 and thereby permits the pressure in the conduit 135 to be manifested in the form of a jet of air emanating from the nozzle 138. This will blow the fragments of material clear of the die so it is again ready to receive a new piece of stock.

In résumé, the operator standing in front of the feeding mechanism with his foot upon the pedal 32 places pieces of stock upon the replicas at the stations 46. If he finds that the stock piece is too small to cover the replicas he discards that piece and supplies another in its place. So long as he continues to depress the 60 pedal 32 the cam shaft will operate to perform its various functions and the feeding mechanism and press will operate to produce the desired results. Upon removal of his foot from the pedal 32 both the press and feeding mechanism will be 65 rendered inoperative, since the declutching between the clutch members 23 and 26 will stop the feeding mechanism and therefore the cam shaft. The punch press will then be rendered inoperative since its trip mechanism is no longer acted 70 75

on by the cam 93. From the foregoing it may be seen that a foolproof, safe, and highly efficient device has been disclosed in its preferred form of embodiment, and that many changes and innovations may be incorporated in the design without departing from the principles of the invention as hereinafter claimed. As an example of a change or addition which can be made, suction may be applied at each stock receiving station 46. This is illustrated in Figure 5 wherein the transfer table 35 is provided with a chamber 140 and apertures 141 connecting said chamber with the surface of said table, and the replicas of the parts to be formed are also apertured as at 142 to permit a low vacuum suction to be applied to the stock placed upon said replicas. This is accomplished through the medium of conduits 142 connected to a chamber 143 to which said low vacuum is applied as through a conduit 144. Another addition which may be incorporated is a brake or drag on the table 35 to insure that it does not over-run its feed.

Thus it can be seen that although the present disclosure has been carefully planned and designed, only experience will determine those fine refinements which are necessarily to be incorporated to provide a device of maximum efficiency.

What I claim as new and desire to secure by Letters Patent, is:

1. In combination, a punch press, and means for feeding stock to said press, said means including an intermittently moving member having a plurality of circumferentially arranged stations, for receiving irregularly shaped pieces of stock of greater contour than the contour of the part to be formed therefrom a likeness of the part formed from said stock by said press at each of said stations for guiding the manual positioning of said stock on said member, and means for transferring said stock from said member to said press.

2. In combination, a punch press, means for feeding stock to said press, and means for removing the part formed from said stock from said press, said stock feeding means including an intermittently moving member provided with a plurality of stations, for receiving irregularly shaped pieces of stock of greater contour than the contour of the part to be formed therefrom and a likeness of the mentioned formed part at each station for guiding the positioning of said stock thereon.

3. In combination with a punch and die, an intermittently rotating member, uniformly spaced stations on said member, for receiving irregularly shaped pieces of stock of greater contour than the contour of the part to be formed therefrom a likeness of the piece produced by said punch and die at each station for guiding the position of said stock thereon, means for transferring said stock from said member to said die, and means for removing a formed part from said die.

4. In combination with a punch and die, an intermittently moving member, uniformly spaced stock receiving stations on said member, a likeness of the piece produced by said punch and die at each station for guiding the positioning of said stock thereon, means for transferring said stock from said member to said die, means for removing a formed piece from said die, and means for clearing the die of fragments of stock from which said piece is formed.

5. In combination with a punch press, a member having a plurality of stations each being adapted to support a piece of stock, means for intermittently moving said member, means for transferring a piece of stock from said member to said press, and means for removing said stock from said press, said transferring means and said removing means each comprising a member adapted to oscillate in a substantially horizontal plane and to reciprocate in a substantially vertical plane.

6. In combination, a press having a fixed die, a support for receiving pieces of stock to be fed to said die, means for intermittently rotating said support, said support being provided with stock receiving stations whereby a piece of stock placed upon a station remote from said die is intermittently moved towards said die, and means for transferring a piece of stock from one of the stations nearer to said die to said die.

7. In a device of the character described in combination, a stock support comprising a substantially round member having uniformly spaced stock receiving stations, a die position beyond the periphery of said support, means for intermittently rotating said support whereby a piece of stock placed at a station remote from the die is intermittently carried towards said die, and means for transferring said stock piece to said die from one of the nearer stations.

8. In combination with a punch press, means for driving the press, a separately driven shaft, a stock support, means on said shaft for intermittently moving said support, a plurality of stock receiving stations on said support, means driven by said shaft for transferring said stock from said stations successively to said press, means also driven from said shaft for removing parts formed in said press from said stock, and means controlled from said shaft for coupling the driving means of the press to operate said press synchronously with the movements of the support, the transferring means, and the removing means.

9. In combination, a press having a punch and die, a support for receiving pieces of stock to be fed to said die, means for intermittently moving said support, said support being provided with stock receiving stations whereby a piece of stock placed upon a station remote from said die is intermittently moved towards said die, means for transferring a piece of stock from one of the stations nearer to said die to said die, and means for removing from the press the part formed by said punch in said die.

10. In combination, a press having a punch and die, a support for receiving pieces of stock to be fed to said die, means for intermittently moving said support, said support being provided with stock receiving stations whereby a piece of stock placed upon a station remote from said die is intermittently moved towards said die, means for transferring a piece of stock from one of the stations nearer to said die to said die, means for removing from the press the part formed by said punch in said die, and means for clearing said die of the remainder of the stock from which said part is formed.

11. In combination, a press having a punch and die, a support for receiving pieces of stock to be fed to said die, means for intermittently moving said support, said support being provided with stock receiving stations whereby a piece of stock placed upon a station remote from said die is intermittently moved towards said die, means

for transferring a piece of stock from one of the stations nearer to said die to said die, means for removing from the press the part formed by said punch in said die, and means for clearing the die of the remainder of the stock from which said part is formed, said last mentioned means comprising a nozzle, means for supplying air under pressure to said nozzle, and valve means synchronously operable with the transferring and removing means for supplying a jet of air from said nozzle to the vicinity of the die.

12. In combination, a press having a punch and die, a support for receiving pieces of stock to be fed to said die, means for intermittently moving said support, said support being provided with stock receiving stations whereby a piece of stock placed upon a station remote from said die is intermittently moved towards said die, and means for transferring a piece of stock from one of the stations nearer to said die to said die, said means comprising an arm having a head adapted to engage said stock, and means for applying

suction to said head during engagement thereof with the stock.

13. In combination, a press having a punch and die, a support for receiving pieces of stock to be fed to said die, means for intermittently moving said support, said support being provided with stock receiving stations whereby a piece of stock placed upon a station remote from said die is intermittently moved towards said die, means for transferring a piece of stock from one of the stations nearer to said die to said die, and means for removing from the press the part formed by said punch in said die, said transferring means and said removing means each comprising an arm having a head, means for synchronously moving said arms, and means for applying suction to each head during the transferring and removing movements of the respective arms, and means for breaking said suction at the end of said movements.

MOSES D. HEYMAN.
